UNITED STATES PATENT OFFICE.

CLARENCE D. PLATT, OF BRIDGEPORT, CONNECTICUT.

INCLOSED SWITCH.

1,322,818.

Specification of Letters Patent. Patented Nov. 25, 1919.

Application filed January 2, 1919. Serial No. 269,233.

To all whom it may concern:

Be it known that I, CLARENCE D. PLATT, a citizen of the United States of America, residing at Bridgeport, Connecticut, have invented a new and useful Inclosed Switch, of which the following is a specification.

My present invention is an inclosed switch and the objects of this invention generally are to improve switches of this character by making them more safe and positive in operation, and to provide for the locking of the switch inclosure in the open as well as in the closed condition of the switch circuit.

Briefly stated, the invention may be said to reside in the combination with the switch inclosure, embodying box and cover members, of coöperating switch mechanism and switch operating means mounted in the respective members, and interlocking mechanism on the one member and on the switch operating means on the other member for securing the cover member closed and the operating means interlocked with the switch mechanism when the switch operating means is actuated to close the switch.

Another feature is the provision of coöperating securing means on the one member and on the switch operating means of the other member of the box for securing the cover member closed also when the operating means is shifted to the circuit-open position.

Various other features of the invention and the details of construction will be made clear as the specification proceeds and will be understood from the accompanying drawings wherein I have illustrated the invention embodied in a practical and preferred form.

40 In said drawings:—

Figure 1, is a front or plan view of a switch constructed in accordance with and embodying the invention, one corner of the cover being shown as broken away.

45 Fig. 2, is a cross sectional view thereof taken substantially on the plane of the line 2—2 of Fig. 1.

Fig. 3, is a longitudinal sectional view taken substantially on the plane of the line 50 3—3 of Fig. 1.

Fig. 4, is a side elevation of the switch as locked in the open circuit condition.

The switch inclosure is in the form of a box-like structure embodying a body member 5 and a cover member 6, the latter being movable with respect to the former and

shown as connected thereto by a hinge joint 7.

The switch mechanism illustrated consists of a switch base 8 secured to the bottom or back of the box member and supporting on its face separated contacts 9 and 10 for engagement by the laminated spring contacts 11 and 12 which are mounted on a spring pressed carrier 13 slidably engaged in the posts 14. Connected with the contacts 11 and 12 are the fuse clips 15 and 16 adapted, in this case, to receive a fuse of the cartridge type.

The movement of the combined contact 70 and fuse carrier is effected in the illustration by the pivoted toggle links 17 and 18 which are connected at their outer ends at 19 with the posts and at their inner ends at 20 with the carrier.

75 This switch mechanism which is mounted within the box is shown as protected by an insulating guard 21 provided with apertures 22 through which the fuses project when the switch is in the open circuit position as 80 shown in Figs. 2 and 3.

The switch operating means which is mounted in the cover member consists in the present disclosure, of the rock shaft 23 journaled in the side walls of the cover and 85 provided with dependent rocker arms operating between the spaced shoulders 24 and 25 on the pivoted toggle links to effect the making and breaking of the toggles and hence the closing and opening of the switch. 90 These dependent arms are shown as formed as part of a bracket member 26 secured to the rock shaft. These bracket arms, it will be seen in Fig. 2, form stops limiting the lateral shifting movement of the rock shaft 95 and a spring washer 27 is shown interposed between one of these arms and the adjacent side wall of the cover for frictionally and releasably retaining the rock shaft in the position to which it is turned.

100 The rock shaft is operated by a handle 28 secured on the outer extended end of the same and this handle is provided with an extension 29 projecting beyond the pivotal axis of the handle and carrying the inwardly projecting lug or stud 30 positioned to engage beneath the locking shoulder 31 on the box when the handle is thrown to the circuit-closed position.

110 The stop shoulder described is provided in the present disclosure by means of plates or laminations 32 and 33 of sheet metal built

up to provide the necessary thickness and strength and secured to the side wall of the box as by rivets or other suitable fastening 34. These laminations have coincident lower faces 5 to provide a continuous stop shoulder the full width of the laminations, but the inner laminations 32 are of less height than the outer lamination 33 to receive the dependent edge portion 35 of the cover. The extended 10 or raised edge of the outer lamination 33, provides a stop shoulder 36 positioned to engage the locking lug on the handle when the cover is moved in a closing direction with the handle in the circuit-closed position, thus forming a guard to prevent closure of the cover with the handle in such circuit-closed position. The laminations are also shown provided on their under faces at the end of the track forming the locking 15 shoulder, with a stop shoulder 37, which by engagement with the locking pin limits the switch closing movement of the handle.

The movement of the operating handle in a switch-opening direction is limited by a 20 stop 38 on the back of the handle positioned to engage with the top surface of the cover and a similar stop 39 is shown provided on the back of the handle at the opposite side of its axis for engagement with the upper 25 surface of the cover to limit the throw of the handle in the opposite direction when the cover is open.

Provision is made for locking the handle in the open-circuit position, the same for 30 this purpose consisting in the illustration, of an outstanding lug 40 on the inner or extended end of the handle adapted to register in the circuit-open position of the handle with an outstanding lug or bracket 41 on the 35 box, said lugs having separate registering openings 42 and 43 to receive separate and independent padlocks 44 and 45. This construction enables the locking of the switch in the "off" position by different linemen 40 working on the same circuit and prevents the closing of the switch by one lineman to the injury of the other.

It will be noted that the automatic interlock described secures the cover and 45 prevents opening of the same when the switch is in the circuit-closed condition and similarly the coöperating lock mechanism last described may be used to lock the cover closed and prevent opening of the same 50 when the switch is in the circuit-open position.

In order that the condition of the switch 55 may be known at all times I have shown an indicator in the form of an arcuate member 60 46 on the rock shaft and bearing suitable designations visible through a window or opening 47 in the cover.

I claim:—

1. In a switch of the character described, 65 the combination of a box having a movable

cover, switch mechanism in said box, means for operating said switch mechanism mounted in the cover and disengageable from the switch mechanism on the opening of the cover and engageable with the switch 70 mechanism on the closing of the cover, a shoulder on the box and a locking lug carried by the switch operating means on the cover and positioned to pass beneath the shoulder on the box upon the switch closing 75 movement of said operating means when the cover is closed to thereby secure the cover closed with the operating means interlocked with the switch mechanism and to pass free of said shoulder upon the switch-opening 80 movement of said operating means to thereby permit opening of the cover when the switch is thrown to open position.

2. In a switch of the character described, the combination of a box having a movable 85 cover, switch mechanism in said box, means for operating said switch mechanism mounted in the cover and disengageable from the switch mechanism on the opening of the cover and engageable with the switch 90 mechanism on the closing of the cover, a shoulder on the box, a locking lug carried by the switch operating means on the cover and positioned to pass beneath the shoulder on the box upon the switch closing move- 95 ment of said operating means when the cover is closed to thereby secure the cover closed with the operating means interlocked with the switch mechanism and a stop shoul- 100 der on the box positioned to be engaged by the locking lug on the cover when attempt is made to close the cover with the operating means in the switch closed position.

3. In a switch of the character described, a box member and a coöperating cover mem- 105 ber, switch mechanism mounted in one of said members, switch operating means mounted in the other of said members and having an external handle part and an internal part engageable with the switch 110 mechanism upon the closing of the cover and disengageable therefrom upon the opening of the cover, a locking lug carried by the external part of the operating means on the one member and an external shoul- 115 der carried by the member containing the switch mechanism and positioned to have the locking lug pass beneath and interlock therewith upon switch-closing movement of the operating means with the cover closed, 120 whereby to secure the cover member closed and the operating means interlocked with the switch mechanism.

4. In a switch of the character described, an inclosure comprising a box member and 125 a coöperating cover member, switch mechanism in one of said members and switch operating means in the other of said mem- 130 bers engageable with the switch mechanism upon closing of the cover and disengageable

- therefrom upon opening of the cover and said operating means including a pivoted handle having a swinging extension projecting beyond the point of pivotal support 5 of the handle, a locking lug carried by said swinging handle extension and a shoulder on the member containing the switch mechanism positioned to be engaged by and interlocked with the locking lug upon the 10 switch closing movement of the operating means with the cover member in closed position.
5. In a switch, an inclosure comprising co-operating box and cover members, switch mechanism in one of said members, switch operating means in the other of said members engageable with the switch mechanism on closing of the cover and disengageable therefrom upon opening of the cover, an external locking lug carried by said switch 20 operating means and external stop means on the member containing the switch mechanism and comprising a series of plates provided at one edge with a co-extensive stop 25 face for engagement by the locking lug to secure the cover member closed and one of said plates being extended at its opposite edge to provide a stop for engagement by the locking lug when attempt is made to 30 close the cover with the operating means in the switch-closed position.
6. In combination, a switch box having a movable cover, switch mechanism in the box, a rock shaft pivoted in the cover, dependent means on said rock shaft for operatively engaging the switch mechanism when the cover is closed, a handle on one end of said rock shaft provided with stops at opposite sides of the axis thereof for engagement with the cover to limit the swinging movement of the handle when the cover is open, a locking shoulder on the box and a locking lug on the handle positioned to engage beneath the locking shoulder when the 45 handle is moved in a switch-closing direction with the cover in closed position.
7. In combination, a switch box having a movable cover, switch mechanism in the box, a rock shaft pivoted in the cover, dependent means on said rock shaft for operatively engaging the switch mechanism when the cover is closed, a handle on one end of said rock shaft provided with stops at opposite sides of the axis thereof for engagement with the cover to limit the swinging movement of the handle when the cover is open, a locking shoulder on the box, a locking lug on the handle positioned to engage beneath the locking shoulder when the 55 handle is moved in a switch-closing direction with the cover in closed position, and
- means for releasably securing the handle in the position to which it is turned when the cover is opened and the operating connections are disengaged from the switch 65 mechanism.
8. In combination, a switch box having a movable cover, switch mechanism in the box, a rock shaft pivoted in the cover, dependent means on said rock shaft for operatively engaging the switch mechanism when the cover is closed, an indicator mounted on said rock shaft, a handle on one end of the rock shaft, a locking lug carried by said handle and a stop shoulder on the box positioned to be engaged by said locking lug when said handle is moved in a switch-closing direction and the cover is closed. 70
9. In combination, a switch box having a movable cover, switch mechanism mounted within said box, switch operating means mounted in the cover and including a rocking handle, external co-operating stops on said handle and box for securing the cover closed when the handle is thrown in a switch-closing direction and locking means including parts on the handle and box for securing the cover closed and locking the handle when the handle is thrown to the switch-open position. 75
10. In combination, a switch box having a movable cover, switch mechanism mounted in said box, switch operating means mounted in the cover and including a rocking handle, co-operating stops on said handle and box for securing the cover closed when the handle is thrown in a switch-closing direction and co-operating locking means on the handle and box for securing the cover closed when the handle is thrown to the switch-open 80 position, said latter means including lugs on the handle and box having each a plurality of separated apertures registering in the off-circuit position of the handle to enable the engagement therewith of a plurality of padlocks under the control of different individuals. 85
11. In combination, a switch box having a movable cover, switch mechanism mounted in the box, a rock shaft journaled in the cover, dependent bracket arms secured to said rock shaft providing stops limiting the longitudinal movement of the rock shaft in the cover and engageable with the switch mechanism in the box for operating the 90 same, a handle on the rock shaft, and interlocking mechanism on the box and cover respectively for preventing opening of the cover with the switch in closed-circuit position. 100
